CLAIM

The ornamental design for a golf club grip, as described and shown.

DESCRIPTION

FIG. 1 is a front perspective view of a golf club grip illustrating my new design;

FIG. 2 is a rear elevation view thereof, the side elevation views being identical;

FIG. 3 is a left end elevation thereof; and,

FIG. 4 is a right end elevation thereof.

The broken line showing a golf club shaft in FIGS. 1 and 2 is environmental structure only and does not form part of the claimed invention.
